WOVEN WIRE FABRIC

Charles A. Scheeler, Buffalo, N. Y., assignor to
 Buffalo Wire Works Co., Inc., Buffalo, N. Y., a
 corporation of New York

Application August 26, 1932, Serial No. 630,556

1 Claim. (Cl. 245—6)

This invention relates to a woven wire fabric which is more particularly intended for use as a screen in banks to protect officers from bullets fired from arms in the hands of bandits, but the same may also be used for other purposes.

It is the object of this invention to provide a fabric in which helical transverse wires are interwoven with longitudinal wires so as to produce a product which is closely knit so as to serve as a protection against an attack by bandits using firearms.

In the accompanying drawing:

Fig. 1 is a fragmentary plan view showing the woven wire fabric made in accordance with my improvements.

Fig. 2 is a transverse section of the same taken on line 2—2, Fig. 1.

Similar characters of reference indicate like parts in both figures of the drawing.

Referring to the drawing, the numeral 20 represents a plurality of warp or longitudinal wires which in some instances may be somewhat wavy in the actual fabric, but are represented in the drawing as straight for convenience of illustration. These longitudinal or warp wires are separated from each other a suitable distance to permit of interweaving with them a plurality of helical woof or shoot wires 25 in the manner commonly employed for interweaving the warp and woof or cross wires of a fabric by the use of a loom in the usual and well-known way.

Each of the helical transverse wires has adjacent parts of its turns passing respectively over one of the longitudinal wires and under an adjacent longitudinal wire. The several transverse wires trend successively in opposite directions so that a turn of one of the transverse

wires passes over one of the longitudinal wires and a turn of an adjacent helical wire passes under the same longitudinal wire. In the completed fabric the several helical transverse wires are closely assembled so that the curved parts of the turns of one set of alternate transverse wires are located between adjacent longitudinal wires and trend in one direction and are nested in the curved parts of the turns of the set of alternate transverse wires.

A tightly woven fabric is thus formed which is practically bullet-proof inasmuch as a bullet fired against the same will not be able to penetrate the fabric but instead will rebound or ricochet due to the plurality of inclined surfaces which are presented to the bullet by the turns of the helical transverse wires, and thus save from harm anyone who is protected by this fabric against attack by bandits using firearms.

This fabric is also useful as a fine screen in which a very strong durable surface is required to resist wear and yet sufficient openings must be present to permit any liquid to be drained readily from a mass of solid matter.

I claim as my invention:

A woven wire fabric comprising a plurality of straight longitudinal wires, and a plurality of helical transverse wires, the transverse wires being interwoven with the longitudinal wires so that adjacent transverse wires pass under and over the same longitudinal wire and each transverse wire passes over one and under the next adjacent longitudinal wire, said adjacent helical transverse wires trending in opposite directions and being closely woven whereby the several wires form a tightly woven fabric.
